United States Patent Office

Des. 208,508
Patented Sept. 5, 1967

208,508

BOTTLE CAP

Adolph Klein, Hillsborough, Calif., assignor to The Clorox Company, Cincinnati, Ohio, a corporation of Ohio

Filed May 19, 1966, Ser. No. 2,348

Term of patent 14 years

(Cl. D58—26)

Fig. 1

Fig. 2

Fig. 3

FIG. 1 is a top plan view of a bottle cap showing my new design;

FIG. 2 as an elevational view; and

FIG. 3 is a transverse sectional view of the same.

I claim:

The ornamental design for a bottle cap, as shown.
